UNITED STATES PATENT OFFICE.

JAMES BOOTH, OF WEST NEW BRIGITON, ASSIGNOR TO WHITE, POTTER & PAIGE MANUFACTURING CO., OF BROOKLYN, NEW YORK.

DESIGN FOR MOLDING FOR PICTURE-FRAMES.

SPECIFICATION forming part of Design No. 23,519, dated July 31, 1894.

Application filed May 31, 1894. Serial No. 513,085. Term of patent 3½ years.

To all whom it may concern:

Be it known that I, JAMES BOOTH, a citizen of the United States, and a resident of West New Brighton, in the county of Richmond and 5 State of New York, have invented and produced a new and original Design for a Molding for Picture-Frames or the Like, of which the following is a specification, reference being had to the accompanying drawings, forming part thereof.

Figure 1, is a view of a molding showing my design. Fig. 2, is a cross section on the line *a*, *a*, of Fig. 1.

The leading features of my design consist 15 in the configuration of the frame, and the surface ornamentation placed thereon.

My design is suitable for picture frames and the like, and is to be arranged substantially as shown in the accompanying drawings.

20 In Fig. 1, *A*, *A*, are the two minor moldings or surface ornamentation, which are composed of foliated, or conventionally represented leaves *C*, in relief, with the flower *b*, and ornament *c*, between them, substantially 25 as shown.

The major molding or surface ornamentation *B*, Fig. 1, is disposed between the two minor moldings *A*, *A* and it consists of leaves conventionally represented, the leaves running 30 along parallel with the sides of the frame.

The upper and outer portion of the major molding is also represented by conventional leaves *g*, running along parallel with the exterior of the frame, with here and there an 35 ornamentation as at *h*, between them. The lower line and the upper line of conventional leaves are connected by a leafy representation as at *f*, which is concave, proceeding from the lower line of leaves to the upper, and leav-

ing the upper line of conventional leaves projecting over the concave portion of the molding, at variously, closely proximating points, so as to produce the ornamental effect due to the protrusion over the concave portion of the molding, of the upper conventional leafy 45 representation.

At the corner of the frame there is an ornamentation as at *E*.

It will be seen by reference to Fig. 2, that at the corners of the molding, the protrusion 50 of the upper line of ornamental leaves over the concave portion, is greater in extent, than at any other point, so as to give effect to the corner of the design and make it still more ornamental at that part.

55 At the corner the conventional concave leaves represent a bunch of radiating leaves, as shown at the corner in the drawings at *E*, in which are placed a small flower and rose buds. The bunch of radiating leaves enables 60 the concave leaves, which connect the lower and upper line of conventional leaves, to terminate with good effect at the circular, or more or less circular leafy representation at the corner, gives point to the ornament placed 65 in the circular or partly circular leafy representation at the corner or corners.

I claim—

The design for a molding for picture frames, or the like, substantially as herein shown and 70 described.

Signed at the city of New York, county of New York, and State of New York, this 28th day of May, 1894.

JAMES BOOTH.
